UNITED STATES PATENT OFFICE.

JAMES G. BLUNT, OF SCHENECTADY, NEW YORK.

LATERAL-MOTION APPLIANCE FOR LOCOMOTIVE DRIVING BOXES.

Application filed May 15, 1923. Serial No. 639,046.

To all whom it may concern:

Be it known that I, JAMES G. BLUNT, a citizen of the United States, residing at Schenectady, in the county of Schenectady and State of New York, have invented a certain new and useful Improvement in Lateral-Motion Appliances for Locomotive Driving Boxes, of which improvement the following is a specification.

10 My invention relates to means for affording and controlling lateral motion in the driving boxes of locomotive engines, and its object is to provide an appliance of such type which shall be of simple and substantial construction, readily applicable in present standard designs of locomotives, and in the operation of which the full amount of lateral displacement of the axle shall be made available in the movement of the 20 boxes, in any or all of the driving axles of a locomotive having a comparatively long wheel base, thus making possible the absorption of all curved rail shocks on all the driving axles.

25 The improvement claimed is hereinafter fully set forth.

In the accompanying drawings: Figure 1 is a diagrammatic side view, in elevation, of a Mikado type locomotive, illustrating an 30 embodiment of my invention; Fig. 2, a side view, in elevation, of a locomotive frame pedestal, with an axle and driving box in half vertical transverse section, on the line *a a* of Fig. 3; Fig. 3, a vertical central transverse section through one of the bearing portions of the driving box structure and the pedestal, and a partial side view, in elevation, of the spring seat and interposed accessories; Fig. 4, a side view, in elevation, 35 and on an enlarged scale, of the adjoining end portions of the driving box and spring seat; Fig. 5, a view, half in plan and half in horizontal section, on the line *b b* of Fig. 6, of the spring seat; Fig. 7, a side view of 40 a roller; Fig. 8, an end view of the same; Fig. 9, a plan view of one of the teeth which cooperate with the rollers; Fig. 10, a side view; and, Fig. 11, an end view, of the same.

In the practice of my invention, referring 45 descriptively to the specific embodiment thereof which is herein exemplified, the housings or bearing portions in which the journal bearings, 4^c, are located at the ends of a rigid driving box structure, 4, corresponding substantially to that set forth in Letters Patent of the United States No.

1,057,220, granted and issued to Francis J. Cole, under date of March 23, 1913. The driving box structure may be either formed in two sections, connected, in the longitudinal central plane of the locomotive, by bolts, 4^d, as shown, or be integral from end to end, as preferred, being, in either case, fully adapted to comply with the conditions of existing practice. The end portions of the 60 driving box structure, 4, adjoin the driving wheels, 6, which are secured on opposite ends of the driving axle, 8, and are fitted between the jaws of pedestals, 3, which connect the upper and lower rails, 1 and 2, of 65 the side frame members of the locomotive, and are provided with the usual journal bearings, 4^e, and oil cellars, 4^f.

The portion of the weight of the locomotive which is carried on the driving axle, 75 8, is transmitted to the driving box structure, 4, through springs, 9, which bear centrally, on seats, 10^a, at the ends of a rigid spring seat or supporting beam, 10, extending transversely to the longitudinal central 80 plane of the locomotive, and adapted to move vertically, but not longitudinally, relatively to the side frame members. Chafing plates, 10^b, are fitted between the ends of the spring seat and the inner sides of the 85 top rails, 1, of the side frame members, to take the wear resultant upon the upward and downward movements of the spring seat in service, and lubrication is afforded from oil reservoirs, 10^c, at the ends of the spring 90 seats, which are supplied through openings closed by plugs, 10^d, and from which oil is delivered through openings in which wooden plugs, 10^e, are inserted. It will, of course, be understood that the springs, 9, are connected, by hangers, at their ends, to the side frame members, either directly, or 95 through equalizers, in the ordinary manner.

The ends of the spring seat, 10, are supported on the driving box structure, 4, 100 through the intermediation of transversely extending resistance rollers, 11, which are interposed between the spring seat and driving box structure, adjacent to the ends of the spring seat. The rollers, 11, bear on bearing face recesses, 4^f, on the top of the driving box structure, 4, which recesses are inwardly inclined or curved from their ends to their middle transverse planes, as most clearly shown in Fig. 4, and on similar bearing face recesses, 10^f, on the bottom of the spring seat, 10, and normally rest at 105 110

the middle or intersecting plane of the inclines in the faces of said recesses. The degree of inclination of the opposite inclines of the faces of the recesses is determined by 5 the amount of lateral resistance or centering effort that is desired to be obtained. Recesses, 11^a, formed in the ends of the rollers, 11, are engaged by teeth, 12, having dowels, 12^a, on their inner sides, which teeth are secured 10 in any suitable manner, preferably by being welded, to the opposite sides of the driving box structure and of the spring seat, the dowels fitting in corresponding perforations in said structure and seat. The middle 15 transverse planes of the teeth, 12, coincide with those of the bearing face recesses, 10^b, and 4^c, and stand normally, or when the engine is on a tangent of the track, in line, one with the other.

20 In the operation of an appliance constructed substantially as above described, lateral movement is imparted to the driving box structure, by the sidewise movement of the driving wheels, on entering a curve of 25 the track, and lateral movement of the spring seat, relatively to the side frame members, is prevented by its bearing against their inside faces. The lateral movement of the driving box structure is transmitted to 30 the spring seat, through the engagement of the teeth with the end recesses of the rollers, the teeth and rollers constituting, at all times, the connection between the driving box structure and the spring seat. The 35 travel of the rollers is resisted by the inclination of the bearing face recesses, the degree of which determines the percentage of resistance to free lateral movement, and corresponding percentage of effort exerted to 40 bring the members to, and maintain them in, normal central alignment.

I claim as my invention and desire to secure by Letters Patent:

1. In a locomotive engine, the combination 45 of a side frame; a driving box, fitted, with the capacity of relative longitudinal

movement, therein, and having double inclined bearing face recesses in its top; a spring seat, vertically movable, relatively to the driving box, and having similar bearing face recesses in its bottom; a roller, interposed between the bearing face recesses; and teeth, fixed to the driving box and the spring seat, and engaging said roller. 55

2. In a locomotive engine, the combination of two side frame members; a driving box structure, having end journal bearings, and fitted, with the capacity of relative longitudinal movement, therein, said structure 60 having double inclined bearing face recesses in its top, adjacent to its journal bearings; a spring seat, vertically movable relatively to the driving box structure, and having similar bearing face recesses in its bottom, 65 adjacent to its ends; rollers, interposed between the bearing face recesses; and teeth, fixed to the driving box structure and the spring seat, and engaging said rollers.

3. In a locomotive engine lateral motion 70 appliance, the combination of a driving box, having double inclined bearing face recesses in its top; a transversely extending resistance roller, resting in said bearing face recesses; and teeth, fixed on the driving box, 75 and engaging said roller.

4. In a locomotive engine lateral motion appliance, the combination of side frame members, a rigid spring seat, fitted with the capacity of relative vertical movement 80 only, between said side frame members and having double inclined bearing face recesses underneath its ends, on each side of its bottom; chafing plates, fixed to the side frame members; and oil reservoirs, located 85 on the spring seats and communicating with the chafing plates.

JAMES G. BLUNT.
